United States Patent Office.

JOEL HAYDEN, JR., OF HAYDENVILLE, MASSACHUSETTS.

Letters Patent No. 86,225, dated January 26, 1869.

IMPROVEMENT IN FAUCETS.

The Schedule referred to in these Letters Patent and making part of the same.

To all whom it may concern:

Be it known that I, JOEL HAYDEN, Jr., of Haydenville, Hampshire county, Commonwealth of Massachusetts, have invented a new and improved Faucet; and I do hereby declare that the following is a full and clear description thereof, reference being had to the accompanying drawings, and to the letters of reference marked thereon.

In the drawings—

Figure 1 is a side sectional view of my improved faucet; and

Figure 2 is a detailed view of a part thereof.

This invention consists of a new and useful improved arrangement of parts, whereby a faucet is rendered more perfect in its operation, and less liable to get out of order.

In construction, I form my plug A with a cylindrical tapering face, and neck or stem, B, and the socket or barrel C for this plug is made with a closed bottom end, only opening at the top for the insertion of the plug.

The top outside edge of this barrel is made with threads *a*, upon which screws a cap, D, fitting around the stem B of the plug.

A stop is made by setting in a pin, E, in the plug, at the height of the shoulder *d* of the barrel C, where the threads cease, and the metal being cut out one-quarter of the circumference of the threaded edge of the barrel, this pin plays between the edges *e* and *e* of

this *c* at, the said edges forming the stop for the pin, and enabling the plug to be turned to just the proper positions to cut off completely, or give free passage to the liquid, as may be the case.

A coil-spring is placed around the neck of the plug at *f*, between the cap and the shoulder.

This spring G is compressed down when the cap D is screwed on in place, and assists in packing the cap, as well as producing a friction, to prevent its being loosened.

A vent, H, is made by means of a groove, *g*, running vertically the length of the plug from top to bottom. This allows the fluid to cut off clean, without drip, as it leaves a passage for the air to circulate from the top of the barrel through the nozzle, when the plug is turned off.

By this means I obtain a neat and compact arrangement of parts, and a very effective faucet.

Having described my invention,

What I claim as new, and desire to secure by Letters Patent, is—

The combination of the plug A, vent H, the pin E, and spring G, the cap D, and the socket C, the parts being arranged together and constructed in the manner and for the purpose herein described.

J. HAYDEN, JR.
